(57) **CLAIM**

(**) Term: **14 Years**

Ornamental design of an earphone with a wireless microphone, as shown and described.

(21) Appl. No.: **29/145,271**

DESCRIPTION

(22) Filed: **Mar. 15, 2002**

FIG. 1 is a front perspective view of an earphone with a wireless microphone according to an embodiment of the design;

(30) **Foreign Application Priority Data**

FIG. 2 is a rear perspective view of an earphone with a wireless microphone according to an embodiment of the design;

Feb. 6, 2001 (JP) 2001-006479

FIG. 3 is the front plane view of FIG. 1;

(51) **LOC (7) Cl.** **14-01**

FIG. 4 is the rear plane view of FIG. 1;

(52) **U.S. Cl.** **D14/206**

FIG. 5 is the front elevation view of FIG. 1;

(58) **Field of Search** D14/205, 206,

FIG. 6 is the rear elevation view of FIG. 1;

D14/223, 225-229; 181/129, 130; 379/430,

FIG. 7 is the right-hand side view of FIG. 1;

433; 381/370, 376-381; D24/174

FIG. 8 is the left-hand side view of FIG. 1;

(56) **References Cited**

FIG. 9 is a front plane view of the earphone with a wireless microphone according to an embodiment of the design which shows the microphone being pulled;

U.S. PATENT DOCUMENTS

FIG. 10 is a rear perspective view of an earphone with a wireless microphone according to an embodiment of the design which shows a ear-hook being pulled; and,

FIG. 11 is a view showing an earphone with a wireless microphone according to an embodiment of the design in use.
